[57] **CLAIM**

The ornamental design for a tennis bag, as shown and described.

DESCRIPTION

FIG. 1 is a perspective view of a tennis bag showing my new design;

FIG. 2 is a front elevational view;

FIG. 3 is a rear elevational view;

FIG. 4 is a right side elevational view;

FIG. 5 is a left side elevational view;

FIG. 6 is a rear perspective view;

FIG. 7 is a top plan view with the end straps open;

FIG. 8 is a bottom plan view thereof; and

FIG. 9 is a rear perspective view of an alternate embodiment of the tennis bag wherein shoulder straps are added. The partial showing of surface shading indicating a fabric texture is understood to be continuous throughout on those surfaces where shown.
